CLAIM

The ornamental design for a golf bag shaped shave and utility kit, as shown and described.

DESCRIPTION

FIG. 1 is a front elevational view of a golf bag shaped shave and utility kit showing my new design;

FIG. 2 is a rear elevational view thereof;

FIG. 3 is a left side view thereof; and,

FIG. 4 is right side view thereof.

The top and bottom of the golf bag shaped shave and utility kit are flat and unornamented.
